UNITED STATES PATENT OFFICE.

ARTHUR P. STRONG, OF CHICAGO, ILLINOIS, ASSIGNOR TO GREEN ENGINEERING COMPANY, OF EAST CHICAGO, INDIANA, A CORPORATION OF ILLINOIS.

ASH TANK.

Application filed December 12, 1921. Serial No. 521,964.

To all whom it may concern:

Be it known that I, ARTHUR P. STRONG, a citizen of the United States, residing at Chicago, in the county of Cook and State of Illinois, have invented new and useful Improvements in Ash Tanks, of which the following is a specification.

This invention relates to metal hoppers and tanks for the collection and disposal of ash and other disintegrated materials.

Storage tanks of the type having their walls made of removably mounted sectional plates are not adaptable, as thus made, for use in systems wherein the ash or other material is moved through the pipe lines by suction on the tanks because the joints between the plates are not sealed against the passage of air into the tank.

One object of my invention is to provide means in connection with tanks of this general type whereby they are rendered substantially air tight and thus adaptable to use in pneumatic systems of the kind mentioned.

Another object of my invention is to accomplish this purpose by providing the tank with an outside imperforate wall, thus making the tank of a double wall structure.

A further object of my invention is to employ the imperforate wall as a means for preventing the tank structure from swaying during the building of the sectional inside wall, and thus avoid the use of cross ties as heretofore.

The invention consists further in the matters hereinafter described and more particularly set forth in the appended claims.

In the accompanying drawings—

Fig. 1 is a side elevational view of a storage tank or hopper constructed in accordance with my invention;

Fig. 2 is an enlarged vertical sectional view taken through the tank; and

Fig. 3 is a horizontal sectional view through one of the upright corners of the tank, taken on line 3—3 of Fig. 2.

In the drawings, I have shown a storage tank or hopper of the type having upright side and end walls and a hopper bottom provided with a gate controlled discharge opening, as customary in structures of this general kind. The tank or hopper is usually elevated or supported above the ground or platform, as the case may be, at the distance required to permit emptying of the

tank into a car or truck when moved under the same.

As shown in Fig. 1, the structure includes a plurality of upright supporting posts 1, 1 at the four corners of the tank and extending upward the same distance. These posts support at their upper ends a horizontal base frame 2, from which rise a plurality of upright I-beams 3, 3 laterally spaced apart and forming a portion of the upright side and end walls of the tank.

Extending between and secured to said I-beams 3, 3 are cross-members 4, 4 horizontally arranged and spaced apart vertically. The cross-members 3, 3 are of channel shape to accommodate the hooks 5 of plate supporting bars or members 6. These bars extend downward and are channeled along their side edges to receive and support the plates 7, 7 which form the inner wall of the tank. This construction is substantially like that disclosed in Patent No. 1,243,873, granted October 23, 1917, to H. A. Poppenhusen and myself, and needs no further description herein, except to remark that the plates 7, 7 in the various vertical rows overlap each other along their upper and lower edges, respectively, on the inside of the wall and have a sliding connection with the members 6 so that the inner wall of the tank may be built up and, further, be readily taken apart for repair.

To adapt such type of tank or hopper to a suction type of system, that is, a system wherein the ash or other material being handled is drawn through the pipe line by a suction on the tank, I have encased the sectional wall of the tank in an imperforate casing so as to make the tank substantially air tight to hold a suction. This casing is arranged outside of the sectional inner wall and comprises a plurality of plates 8, 8 for the upright wall of the tank and similar plates 9, 9 for the hopper bottom.

In the upright wall of the tank, the plates 8, 8 are arranged in horizontal and vertical rows and have their side edges riveted or otherwise rigidly secured to the upright members or I-beams 3, 3 on the outside thereof, as shown in the drawings. The uppermost plates 8, 8 have their upper edges riveted or otherwise secured to the frame member 10 extending about the top of the tank and from which the uppermost plates 7 of the inner walls are suspended, as shown

in Fig. 2. The top wall 11 of the tank is also made of plates suitably shaped and riveted or otherwise secured to the framework 12 of said top wall.

5 At the center of the top wall 12 there is an inlet pipe 13 connected to the pipe line of the system, and at one side of the center is a pipe 14 whereby the required suction may be placed on the tank for conveying the 10 material from the pipe line into the tank, as customary in ash conveying and like systems of suction type.

The lowermost plates 8, 8 of the upright marginal wall of the tank have their lower 15 edges riveted or otherwise secured to a channel member 15 on top of the I-beams of the base frame 2 and from this member rise the uprights 3, as shown in Fig. 2. The uppermost plates 7, 7 forming the inside of 20 the hopper bottom are suspended from members 16 associated with this channel member 15.

The uppermost outside plates 9 of the hopper bottom are flanged outward, as it 25 17; and are secured to the under side of the I-beams of the base member 2, as shown in Fig. 2. The base member 2 thus closes the space between the lowermost outside plates 8, 8 of the upright tank wall and the uppermost outside plates 9, 9 of the hopper bottom, with the result that no air can leak into 30 the tank around the base member 2 to impair the suction on the tank.

The gate structure at the bottom of the 35 hopper includes a gate casting 18 surrounding the outlet opening in the bottom of the hopper and this casting has an outwardly extending flange 19 surrounding the same. The lower margins of the lowermost outside 40 plates 9 of the hopper bottom are flanged, as at 20, and are suitably secured by rivets or otherwise to the flange 19, as shown in Fig. 2. This provides an air seal at this point.

45 The construction at each of the four corners of the hopper is as shown in Fig. 3. As there illustrated, the inner wall of the hopper is formed of vertically arranged sectional plates 21, shaped to form a corner and supported by the hook carrying members 6 at the side edges of such plates. The outside wall or casing at the corner includes the plate 8 at such corner and one plate has a flanged side edge, as at 22, to overlap the 50 edge of the adjacent plate 8 and is riveted or otherwise secured thereto. As shown in Fig. 2, the outside plates 8 in the upright walls overlap each other, as at 23, between the uprights 3, to form an air seal between 55 such edges of such plates; while the outside plates 9 in the hopper bottom overlap, as at 24, between the inclined end members of the supporting structure of the hopper bottom, to make an air seal at such points.

60 65 By the construction described, the tank

walls are made double, that is, there is an inner wall against which contacts the material discharged into the hopper and an outer wall, the latter being so made as to make the tanks substantially air tight and thus adapt itself to those types of systems which progress the material through the pipe line by a suction on the tank. The plates of the two walls are spaced apart by the interposed framework of the tank structure and supported by that framework. One of the walls of the tank is formed of removable plates so that such wall may be repaired when desired and, furthermore, permit the building up of that wall as the tank is installed. The outside walls being formed of rigid plates rigidly connected with the framework of the tank structure makes the entire unit supported by the four posts 1, 1, and thus allows building up of the inner wall without the use of tie rods for the upright wall of the tank. This outside wall being a supporting unit, prevents the tank from swaying and avoids the use of tie rods for that purpose as heretofore made necessary. The inside plates 7, 7 of the hopper bottom are suspended from the cross-members 25 of that structure, as shown.

90 While I have shown and described herein in an ash tank or hopper embodying the features of my invention, it is of course to be understood that the details of construction and arrangement of parts as shown may be variously changed and modified without departing from the spirit and scope of my invention.

95 I claim as my invention:

1. A tank, comprising an upright marginal wall and a bottom wall, said walls being formed of a plurality of sectional plates removably mounted on the framework of the tank structure, and means associated with said walls for preventing air being drawn into the tank when placed under suction. 105

2. A tank, comprising an upright marginal wall and a bottom wall, said walls being formed of a plurality of sectional plates removably mounted on the framework of the tank structure, and means surrounding said walls for preventing air being drawn into the tank when placed under suction. 115

3. A storage tank, comprising an upright marginal wall and a hopper bottom, said upright wall and hopper bottom being formed of a plurality of sectional plates removably engaged with the framework of the tank structure, and means surrounding said upright wall and hopper bottom for preventing air being drawn into the tank when placed under suction. 120

4. A tank, comprising inner and outer walls, spaced apart and both formed of 130

plates engaged with the framework of the tank structure between said walls, the plates of one wall being rigidly secured to the framework to prevent air being drawn into the tank when the latter is placed under suction, and the plates of the other wall being removably engaged with said framework.

5. A tank, comprising inner and outer walls, spaced apart and both being formed of plates engaged with the framework of the tank between said walls, the plates of the inner wall being removably engaged with the framework, and the plates of the outer wall being rigidly engaged with the framework to prevent air being drawn into the tank through the inner wall when the tank is placed under suction.

6. A tank, comprising inner and outer walls, a framework between said walls, one of said walls being formed of a plurality of plates rigidly secured to the framework, and the other wall being formed of a plurality of removable plates suspended from the framework.

7. A tank, comprising inner and outer walls, a framework between said walls and including upwardly extending and transverse members, one of said walls being formed of a plurality of plates rigidly secured to the framework, and the other wall being formed of a plurality of removable plates suspended from the transverse members.

35. 8. A tank, comprising inner and outer walls, a framework between said walls including upwardly extending and transverse members, the outer wall being formed of a plurality of plates rigidly secured to the upwardly extending members, and the inner wall being formed of members hooked over the transverse members, and removable plates between and supported by said hooked members.

45. 9. A storage tank, comprising upright posts, a horizontal base frame at the upper ends of said posts and supported thereby, laterally spaced members resting on and extending upward from said base frame, vertically spaced horizontal members extending between and secured to said upright members, downwardly inclined members secured at their upper ends to said base frame, horizontal members extending between said

downwardly extending members, inner and outer plates secured to said framework and forming the upright marginal wall and hopper bottom of the tank, the outside plates being rigidly secured to the framework to prevent air being drawn into the tank when the latter is placed under suction, and the inside plates having removable connection with said framework.

55. 10. A tank, comprising an upright marginal wall and a hopper bottom, said upright wall and hopper bottom being formed of a plurality of sectional plates removably engaged with the framework of the tank structure, means surrounding said upright wall and hopper bottom for preventing air being drawn into the tank when placed under suction, and means providing an air seal between said upright wall and hopper bottom.

60. 11. A tank, comprising an upright marginal wall and a hopper bottom, said marginal wall and hopper bottom being formed of a plurality of inside and outside plates, the outside plates being rigidly secured to tank framework for preventing air being drawn into the tank when under suction, the inside plates being removably engaged with said framework, and a base member surrounding the tank between the upper and lower margins of said hopper bottom and upright wall, respectively, for providing an air seal between such parts.

65. 12. A tank, comprising a horizontal base frame, an upright marginal wall rising from and supported by said frame, a hopper bottom hung from said frame, said upright wall and hopper bottom both being formed of a plurality of inner and outer plates, the former being removably engaged with the tank framework between the plates, the outer plates being rigidly secured to said framework to prevent passage of air into the tank when placed under suction, and a gate casting surrounding the discharge opening in the bottom of said hopper, the lowermost outer plates of said hopper being flanged and secured to said casting for providing an air seal between such parts.

70. In testimony that I claim the foregoing as my invention, I affix my signature this 9th day of December, A. D. 1921.

ARTHUR P. STRONG.
